WESLEY BRADLEY, OF VIENNA, MAINE.

Letters Patent No. 78,419, dated June 2, 1868.

IMPROVED CART-BODY.

The Schedule referred to in these Letters Patent and making part of the same.

TO ALL WHOM IT MAY CONCERN:

Be it known that I, WESLEY BRADLEY, of Vienna, county of Kennebec, and State of Maine, have invented a new and useful "Improvement in Cart-Bodies;" and I do hereby declare that the following is a full and exact description of the same, reference being had to the accompanying drawings, and to the letters and figures marked thereon, explaining the mode and use of my improvements.

Figure 1 is a view of a cart-body, showing the "tail-board" of the same fastened or held in place by the improvements claimed.

Figure 2 shows the "unfastening" and mode of taking out of the "tail-board," with said improvements.

My improvement consists in fastening the "tail-board" in such a manner that it can be easily and readily loosened and taken out, although there may be a great pressure from the load inside the cart-body, even when the cart-body is "tipped up" at any angle needed for dumping or unloading the same.

By my improvement, also, a tail-board of any width is kept in place, simply by having some cleats fastened upon it, just inside of the rods that hold it in, thereby preventing its becoming loose and coming out by any jolting of the cart when unloaded or otherwise.

In fig. 1, a common cart-body is represented with a tail-board, A, held in place by a common rod, B, and by my improved rod C, which is made of common round iron, and bent at different angles, as shown, with a handle, D, and fastened with a small iron pin, E.

This fastening may be by a spring-catch or snap instead, if chosen.

The angles in this rod, as shown at C and F, are about one and a half inch, passing at the bottom into the sill of the cart, and at the top through the rail, and through a thin plate of iron fastened thereon, as shown at L.

Fig. 2 shows the mode of unfastening and taking out the tail-board, which is by taking out the pin E, and bringing or turning the rod half round, as at G, which brings the rod outside of the end of the tail-board, thereby leaving it free to be taken out. The rod B should be set as far to the right as practicable, which will allow the other end of the tail-board the more easily to come out. The cleats H H are to be put on when the tail-board is not wide enough to have notches cut in the top of it, to come between the top rails of the cart, as shown at J J, in which case they are not needed.

What I claim, and desire to secure by Letters Patent, is—

The bent rod C, provided with the handle, in combination with the pin for fastening, as shown, for the purpose herein described and set forth.
